UNITED STATES PATENT OFFICE

2,206,071

CONVERSION OF HYDROCARBON OILS

Charles H. Angell, Chicago, Ill., assignor to Universal Oil Products Company, Chicago, Ill., a corporation of Delaware

Application April 30, 1937, Serial No. 139,884

8 Claims. (Cl. 196—48)

This invention particularly refers to an improved process and apparatus for the fractional distillation of hydrocarbon oils of relatively wide boiling range, accompanied by the pyrolytic conversion of selected low-boiling and intermediate fractions of the charging stock under independently controlled heating conditions, treatment of selected high-boiling fractions of the charging stock in commingled state with hot conversion products resulting from one or both of the aforementioned cracking operations and further conversion of intermediate liquid products of the cracking operation together with said intermediate fractions of the charging stock. The process is operated for the production of high yields of good quality motor fuel and minor yields of either liquid residue, such as good quality fuel, or petroleum coke; the coking step, when employed, being assisted by directly commingling with the materials undergoing coking regulated quantities of the highly heated conversion products resulting from that step of the process to which said selected low-boiling fractions of the charging stock are supplied.

One of the important advantages of the invention resides in the provisions whereby high-boiling fractions of the charging stock recovered in the distilling operation may be subjected to appreciable cracking in a reaction chamber of the system by commingling the same therein with highly heated products resulting from conversion of the selected low-boiling and intermediate fractions of the charging stock, without passing said high-boiling fractions of the charging stock through a cracking coil. This feature obviates the excessive formation of coke and gas, which is often encountered in cracking such relatively heavy oils in a heating coil, without sacrificing the additional yields of gasoline which are obtainable by cracking said heavy fraction of the charging stock.

Another advantageous feature of the invention resides in the provisions whereby the total intermediate liquid conversion products of the process are subjected, in commingled state, with said selected intermediate fractions of the charging stock, to conversion in the same heating coil under more severe cracking conditions than those afforded the high boiling fractions of the charging stock. Except for this feature, the present invention is closely related to the process of my issued United States Patent No. 2,070,249, which discloses a combination topping and selective cracking system wherein intermediate and high-boiling charging stock fractions are

supplied from a distilling step to the fractionator of a cracking system, their high-boiling components commingling therein with high-boiling fractions of the intermediate liquid conversion products and being directed therewith to the reaction chamber of the cracking system, while their low-boiling components are passed, together with selected low-boiling fractions of the intermediate liquid products, through a cracking coil into the reaction chamber.

I have found that it is often advantageous to subject the total reflux condensate (intermediate liquid conversion products) to the same cracking conditions afforded the intermediate fractions of the charging stock, since, with most types of charging stock, said reflux condensate (which is the result of initial cracking of the charging stock or selected fractions thereof) is more refractory to cracking than virgin charging oil of similar boiling range characteristics and, therefore, the high-boiling fractions of said intermediate liquid products require more severe conversion conditions, to produce good quality gasoline, than do the high-boiling fractions of the virgin charging stock. The present process is particularly directed to a specific improvement over the process disclosed in the aforementioned issued patent whereby the total intermediate liquid conversion products of the process are subjected to further cracking in commingled state with selected intermediate fractions of the charging stock and under more severe cracking conditions than those afforded the high boiling fractions of the virgin charging oil.

The invention resides in the cooperative combination between the various steps of the process, each of which are interdependent and mutually contribute to produce the desired final results. The entire process may be conducted in a relatively simple unified system and is sufficiently flexible in operation to permit the advantageous treatment of practically any type of hydrocarbon oil of relatively wide boiling range to produce one or more types of gasoline and to produce either good quality liquid residue or coke, as desired.

One specific embodiment of the invention comprises subjecting a hydrocarbon oil of relatively wide boiling range, such as crude petroleum, for example, to fractional distillation, whereby it is separated into selected relatively low-boiling, intermediate and high-boiling fractions, recovering any components of said low-boiling fractions which boil within the range of gasoline and are of satisfactory antiknock value, subjecting another selected portion of said low-boiling

fractions, including any poor antiknock gasoline components of the charging stock, to cracking conditions of elevated temperature and superatmospheric pressure regulated to effect the production therefrom of high yields of good antiknock gasoline, introducing all or a regulated quantity of the resultant hot conversion products into an enlarged reaction zone also maintained at substantial superatmospheric pressure wherein they are afforded additional conversion time, subjecting said selected intermediate fractions of the charging stock to independently controlled cracking temperature at superatmospheric pressure, supplying resultant heated products to said enlarged reaction chamber, simultaneously supplying to said reaction chamber said selected relatively high-boiling fractions of the charging stock, without previously heating the same to cracking temperature, whereby they are subjected to conversion in said reaction chamber in commingled state with said hot conversion products supplied thereto and by means of heat derived from the latter, separating vaporous and liquid conversion products resulting from the cracking afforded the commingled materials in said reaction chamber and subjecting said liquid products to appreciable further vaporization at substantially reduced pressure, subjecting the vaporous conversion products, including those evolved by said further vaporization of the liquid products, to fractionation whereby their components boiling above the range of gasoline are condensed as reflux condensate, returning said reflux condensate to the same cracking zone, preceding said reaction chamber, to which said intermediate fractions of the charging stock are supplied, subjecting fractionated vapors of the desired end-boiling point to condensation and recovering the resulting products.

The accompanying diagrammatic drawing illustrates one specific form of apparatus in which the improved process of the invention may be conducted.

Raw oil charging stock for the process, comprising crude petroleum or any other hydrocarbon oil of relatively wide boiling range which preferably contains an appreciable quantity of gasoline or gasoline fractions, all or a substantial portion of which may be of inferior antiknock value, is directed through line 1 and valve 2 to pump 3 by means of which it is fed through line 4 and valve 5 to heating coil 6 and therein heated, by means of heat supplied from a furnace 7, to a temperature adequate to effect its substantial subsequent vaporization and fractionation. The heated charging stock is directed from heating coil 6 through line 8 and valve 9 into distilling and fractionating column 10, wherein its separation into selected relatively low-boiling intermediate and high-boiling fractions, is effected. It is, of course, also within the scope of the invention to heat the charging stock to the desired distilling temperature in any other well known manner, not illustrated, such alternative methods comprising, for example, indirect heat exchange between the charging stock and relatively high intermediate or final products of the cracking operation or, when desired, such indirect heat exchange may be utilized in combination with the heating coil.

The low-boiling fractions of the charging stock may be recovered as one or a plurality of streams from the distilling and fractionating column, provision being made for removing all or the lowest boiling portions of the same as an overhead prod-

uct from the upper portion of the fractionator, wherefrom they are directed through line 11 and valve 12 to condensation and cooling in condenser 13, the resulting distillate and any uncondensed gases passing through line 14 and valve 15 to collection and separation in receiver 16. When the condensed gasoline or low-boiling gasoline fractions are of satisfactory antiknock value, they may be recovered from receiver 16 as a final product of the process by removing the same therefrom through line 17 and valve 18 to storage or elsewhere, as desired. Any uncondensed gaseous materials may be released from the receiver through line 19 and valve 20. When the charging stock does not contain any substantial quantity of gasoline or low-boiling gasoline fractions of satisfactory antiknock value, the total gasoline is preferably collected in receiver 16, either alone or together with somewhat higher boiling fractions of the charging stock such as naphtha, kerosene or kerosene distillate and the like, and is directed therefrom through line 21, valve 22 and line 23 to pump 25 by means of which it is supplied through line 26 and valve 27 to cracking treatment in heating coil 28, as will be later described.

In case some or all of the gasoline components of the charging stock are recovered as a final product of the process from receiver 16, another selected low-boiling fraction thereof, comprising any high-boiling gasoline fractions of inferior antiknock value and/or, when desired, somewhat higher boiling components of the charging stock, such as naphtha, kerosene or kerosene distillate and the like, are separately removed from column 10 and directed through line 23 and valve 24 to pump 25 whereby they are supplied through line 26 and valve 27 to cracking treatment, as will be later described, in heating coil 28.

Intermediate fractions of the charging stock comprising, for example, selected components thereof such as heavy naphtha fractions, kerosene or kerosene distillate, gas oil and the like, are removed from a suitable intermediate point from column 10 and directed through line 29 and valve 30 to pump 31 by means of which they are supplied through line 32, valve 33 and line 62 to conversion in heating coil 34, as will be later described.

The remaining relatively high-boiling fractions of the charging stock or selected components thereof are removed from the lower portion or, when desired, from a suitable intermediate point in column 10 and directed through line 35 and valve 36 to pump 37 by means of which they are fed through line 38 and may be directed, all or in part, either through valve 39 in this line into reaction chamber 40 or, all or in part, through line 41 and valve 42 into chamber 43. Preferably, the total high-boiling fractions of the charging stock are supplied, as described, to chamber 40 and therein subjected to cracking in commingled state with heated products from heating coil 28 and/or heating coil 34, as will be later explained in more detail, but said high-boiling fractions may, when desired, be supplied, as described, to chamber 43, for further vaporization therein and wherein they may, when desired, be reduced to coke or wherefrom their unvaporized components may be recovered as residual liquid.

The oils supplied to heating coil 34 are heated therein to the desired cracking temperature, preferably at a substantial superatmospheric pressure, by means of heat supplied from a furnace 44, and the heated products are directed

from heating coil 34 through line 45 and valve 46 into reaction chamber 40.

The relatively low-boiling oils supplied, as previously described, to heating coil 28 are heated therein preferably to a higher temperature than that employed in heating coil 34, preferably at a substantial superatmospheric pressure, by means of heat supplied to this zone from furnace 47. The conversion conditions maintained in coil 28 are preferably regulated to effect a substantial improvement in the antiknock value of any gasoline or gasoline fractions supplied thereto, without excessively altering their boiling range. This is commonly termed reforming and, since conditions within the reforming range may be so selected that they are also suitable for cracking naphtha, kerosene or kerosene distillate and the like, one or more oils of the latter type may be included in low-boiling oils supplied to heating coil 28, whereby to produce additional yields of good quality gasoline therefrom.

The highly heated conversion products are discharged from heating coil 28 through line 48 and preferably a substantial portion or all of these products are directed through line 49 and valve 50 into reaction chamber 40, although a regulated portion or all of the heated products discharged from heating coil 28 may, when desired, be directed through valve 51 in line 48 into chamber 43, particularly in case high-boiling fractions of the charging stock from column 16 are supplied to chamber 43 for reduction therein to coke.

Chamber 40 is also preferably operated at a substantial superatmospheric pressure which may be substantially the same as that employed in the communicating heating coil utilizing the lowest pressure or may be somewhat lower than that employed in either of these heating coils. The hot conversion products thus supplied to chamber 40 from heating coil 28 and/or heating coil 34 commingle in this zone with the high-boiling fractions of the charging stock supplied thereto and serve to heat the latter to a suitable cracking temperature.

The heat exchange thus effected in chamber 40 also serves to partially cool the heated conversion products and prevent their excessive further conversion in this zone. The conversion afforded the commingled materials in chamber 40 is regulated to effect the production of appreciable additional quantities of desirable low-boiling materials from the high-boiling fractions of the charging stock supplied to this zone under the temperature and pressure conditions prevailing therein and, in the particular case here illustrated, the commingled materials after passing through substantially the entire length of the reaction chamber are removed from the lower portion of this zone in commingled state through line 52 and directed therefrom through valve 53 into chamber 43. It is, however, also within the scope of the invention to separately remove vaporous and liquid conversion products from chamber 40 in any well known manner, not illustrated, and, when desired, provision may be made for subjecting the various streams of materials supplied to this zone or vaporous and liquid components of the several streams to different conditions of treatment in chamber 40, by the use of suitable well known means such as wall-washing devices and the like, not illustrated, whereby segregation of the vaporous and liquid conversion products may be accomplished in chamber 40 and/or by introducing some or all of

the various streams into chamber 40 at different points in this zone.

Chamber 43 is preferably operated at a substantially reduced pressure relative to that employed in chamber 40, whereby appreciable further vaporization of the liquid conversion products supplied thereto from reaction chamber 40 is accomplished. In case chamber 43 is operated as a coking zone, the coking operation is preferably assisted by introducing regulated quantities of the highly heated product from the heating coil 28 into direct contact with the materials undergoing coking therein. The coke produced may be allowed to accumulate within chamber 43 until this zone is substantially filled, or until the operation thereof is completed for any reason, following which the chamber may be cleaned and prepared for further operation, preferably after it has been isolated from the rest of the system. Chamber 43 is provided with line 54 controlled by valve 58 through which liquid residue may be removed from the chamber, when the system is operated for the production of such material in this zone, and this line may also serve as a means of introducing steam, water or other suitable cooling material into the chamber, when the latter is operated as a coking zone, to hasten cooling and facilitate removal of the coke after the operation of the chamber is completed. Preferably, although only a single coking chamber is illustrated in the drawing, a plurality of such zones is preferably employed and the various coking chambers preferably are alternately operated, cleaned and prepared for further operation in order that this stage, in common with the rest of the system, may be operated continuously.

The vaporous products evolved in chamber 43 are directed from the upper portion thereof through line 56 and valve 57 to fractionation in fractionator 58, whereby their components boiling above the range of the desired gasoline product of this stage of the system are condensed as reflux condensate.

Preferably, the total reflux condensate formed in fractionator 58 is directed from the lower portion of this zone through line 59 and valve 60 to pump 61, by means of which it is returned through line 62 and valve 63 to further conversion in heating coil 34, together with the intermediate fractions of the charging stock supplied thereto, as previously described.

Fractionated vapors of the desired end-boiling point are withdrawn, together with gaseous conversion products of the process, from the upper portion of fractionator 58 and directed through line 64 and valve 65 to condensation and cooling in condenser 66. The resulting distillate and gases pass through line 67 and valve 68 to collection and separation in receiver 69. The distillate, preferably comprising gasoline of good antiknock value, may be removed from receiver 69 through line 70 and valve 71 to storage or to any desired further treatment. The uncondensed gases may be released from the receiver 69 through line 72 and valve 73.

When desired, regulated quantities of the distillate collected in receiver 69 may be recirculated, by well known means not illustrated, to the upper portion of fractionator 58 to serve as a cooling and refluxing medium in this zone. Also, when desired, this same well known expedient may be utilized for controlling fractionation in column 10, by returning regulated quantities of the distillate collected in receiver 16 to the upper portion 75

thereof, by well known means, not illustrated. The preferred range of operating conditions, which may be employed in conducting the process in an apparatus such as illustrated and above described, may be approximately as follows:

The temperature to which the charging stock is heated for the purpose of effecting its fractional distillation may range, for example, from 450 to 700° F. or more, depending primarily upon the characteristics of the charging stock employed and the pressure utilized in the distilling zone. Any desired pressure ranging from substantially atmospheric to a superatmospheric pressure of 100 pounds or more per square inch, may be employed in the heating coil of the distilling step and substantially the same or lower pressure may be utilized in the distilling and fractionating column. In most cases, the distilling operation is conducted at substantially atmospheric pressure and the charging stock is heated prior to its introduction into the distilling column to a temperature of from 550 to 700° F., or thereabouts.

The temperature to which the intermediate fractions of the charging stock and the intermediate liquid conversion products of the process are heated, as measured at the outlet from the heating coil wherein these materials are subjected to conversion in commingled state, may range, for example, from 900 to 975° F. or thereabouts, preferably with a superatmospheric pressure at this point in the system of from 100 to 500 pounds or more per square inch.

The superatmospheric pressure employed in the reaction chamber may range, for example, from 100 to 500 pounds or thereabouts per square inch and, as previously mentioned, may be substantially the same or somewhat lower as that employed in the communicating and heating coil utilizing the lowest pressure.

The heating coil to which said selected low-boiling fractions of the charging stock are supplied, may employ an outlet conversion temperature ranging, for example, from 950 to 1050° F. or thereabouts, preferably with a superatmospheric pressure at this point in the system of from 200 to 800 pounds or more per square inch.

The vaporizing or coking chamber succeeding the reaction chamber, preferably, as previously mentioned, is operated at a substantially reduced pressure relative to that employed in the reaction chamber, which may range, for example, from a superatmospheric pressure of 150 pounds or thereabouts per square inch down to substantially atmospheric pressure and this pressure may be either substantially equalized or reduced in the succeeding fractionating, condensing and collecting portions of the cracking system.

As a specific example of an operation of the process conducted in an apparatus such as illustrated and above described: The charging stock is a mixed base crude of about 28° A. P. I. gravity, containing approximately 31% of straight-run gasoline boiling up to 437° F. which includes approximately 17%, based on the charging stock, of gasoline fractions of good antiknock value boiling up to approximately 300° F. The charging stock is heated to a temperature of about 650° F. at a superatmospheric pressure of about 75 pounds per square inch and the heated oil is introduced into a distilling and fractionating column operated at substantially atmospheric pressure wherefrom the gasoline fractions of the crude boiling up to approximately 300° F. are recovered as overhead distillate. Other low-boiling components of the charging stock, comprising

heavy gasoline and naphtha fractions amounting to approximately 23% of the charging stock and having an end-boiling point of approximately 520° F., are separately removed as a side-stream from the distilling and fractionating column and supplied to the light oil cracking or reforming coil of the system. Intermediate fractions, comprising an additional 30% or thereabouts of the charging stock, are separately recovered as a side-stream from the distilling and fractionating column and supplied to the other cracking coil of the system. The remaining 30% or thereabouts, comprising the heavy fractions of the crude are removed from the lower portion of the distilling and fractionating column and supplied directly to the reaction chamber of the cracking system. The coil to which said intermediate fractions are supplied employs an outlet conversion temperature of approximately 950° F. and a superatmospheric pressure, measured at the outlet from this zone, of approximately 350 pounds per square inch, which pressure is substantially equalized in the reaction chamber to which the heated products from this zone are supplied. The light oil cracking or reforming coil is operated at an atmospheric pressure of approximately 750 pounds per square inch, as measured at the outlet from this zone, and the temperature of the heated products discharged therefrom is approximately 990° F. Approximately 65% of the heated products from the last mentioned coil are supplied to the reaction chamber and the remaining 35% or thereabouts are introduced into alternately operated coking chambers to which both vaporous and liquid conversion products from the reaction chamber are supplied. The vaporous components of the commingled materials supplied to the reaction chamber are afforded a longer conversion time than their liquid components in this zone by supplying all of said materials to the upper portion of the reaction chamber and removing the same in commingled state from its lower portion to the coking zone. Vaporous products from the coking zone are subjected to fractionation and the total reflux condensate resulting from said fractionation is returned for further cracking to the same heating coil to which said intermediate fractions of the charging stock are supplied. The coking zone is operated at an atmospheric pressure of approximately 80 pounds per square inch and this pressure is substantially equalized in the succeeding fractionating, condensing and collecting portions of the cracking system. This operation will produce approximately 68%, based on the crude charging stock, of 400° F. end-point gasoline. The final gasoline product, which is a blend of that produced by the cracking and reforming operations with the straight-run fractions recovered from the topping step, has an octane number of more than 70 by the motor method. The additional products of the process comprise approximately 68 pounds of good quality petroleum coke and approximately 650 cubic feet of rich uncondensable gas per barrel of crude charging stock.

I claim as my invention:

1. A process for the treatment of hydrocarbon oils which comprises subjecting raw oil charging stock for the process to fractional distillation and thereby separating the same into selected low-boiling, intermediate and high-boiling fractions, heating said intermediate fractions to cracking temperature at superatmospheric pressure in a heating coil, introducing the resulting heated products into an enlarged reaction chamber, re-

- covering any components of said low-boiling fractions which boil within the range of gasoline and are of satisfactory antiknock value, heating the remainder of said low-boiling fractions, including any gasoline components of the charging stock which are of unsatisfactory antiknock value, to a higher cracking temperature at substantial superatmospheric pressure in a separate heating coil, introducing at least a portion of the resultant highly heated products into said reaction chamber, commingling said high-boiling fractions of the charging stock, without previously heating the same to cracking temperature, with the heated products supplied to said reaction chamber and maintaining the commingled materials in said reaction chamber at a sufficiently high cracking temperature and superatmospheric pressure to effect appreciable cracking of said high-boiling fractions in this zone, removing the resulting vaporous and liquid conversion products from the reaction chamber, subjecting the liquid products to appreciable further vaporization in a zone of substantially reduced pressure relative to that employed in the reaction chamber, subjecting the vaporous conversion products, including those resulting from said further vaporization of the liquid products, to fractionation independently of the charging stock for the formation of a single reflux condensate containing substantially all components of said vaporous products heavier than gasoline, subjecting fractionated vapors of the desired end-boiling point to condensation, recovering the resulting distillate and returning said reflux condensate formed by said fractionation, including intermediate liquid conversion products boiling above the range of said intermediate fractions of the charging stock, to the first mentioned heating coil for further cracking.
2. A process for the treatment of hydrocarbon oils which comprises subjecting raw oil charging stock for the process to fractional distillation and thereby separating the same into selected low-boiling, intermediate and high-boiling fractions, heating said intermediate fractions to cracking temperature at superatmospheric pressure in a heating coil, introducing the resulting heated products into an enlarged reaction chamber, recovering any components of said low-boiling fractions which boil within the range of gasoline and are of satisfactory antiknock value, heating the remainder of said low-boiling fractions, including any gasoline components thereof of the charging stock which are of unsatisfactory antiknock value, to a higher cracking temperature at substantial superatmospheric pressure in a separate heating coil, introducing at least a portion of the resultant highly heated products into said reaction chamber, commingling said high-boiling fractions of the charging stock, without previously heating the same to cracking temperature, with the heated products supplied to said reaction chamber and maintaining the commingled materials in said reaction chamber at a sufficiently high cracking temperature and superatmospheric pressure to effect appreciable cracking of said high-boiling fractions in this zone, removing the resulting vaporous and liquid conversion products from the reaction chamber, subjecting the liquid products to appreciable further vaporization by supplying the same to said separate chamber, subjecting the vaporous conversion products, including those resulting from said further vaporization of the liquid products to fractionation independently of the charging stock for the formation of a single reflux condensate containing substantially all components of said vaporous products heavier than gasoline, subjecting fractionated vapors of the desired end-boiling point to condensation, recovering the resulting distillate and returning said reflux condensate formed by said fractionation, including intermediate liquid conversion products boiling above the range of said intermediate fractions of the charging stock, to the first mentioned heating coil for further cracking.
3. A process such as defined in claim 1 wherein regulated quantities of the highly heated products from said separate heating coil are directly commingled with the liquid products undergoing vaporization in said zone of substantially reduced pressure and assist in reducing the latter to substantially dry coke in this zone.
4. A process such as defined in claim 1 wherein vaporous and liquid conversion products are withdrawn in commingled state from said reaction chamber and introduced into said zone of substantially reduced pressure.
5. A process for the treatment of hydrocarbon oils which comprises subjecting raw oil charging stock for the process to fractional distillation and thereby separating the same into selected low-boiling, intermediate and high-boiling fractions, heating said intermediate fractions to cracking temperature at superatmospheric pressure in a heating coil, introducing the resulting heated products into an enlarged reaction chamber, recovering any components of said low-boiling fractions which boil within the range of gasoline and are of satisfactory antiknock value, heating the remainder of said low-boiling fractions, including any gasoline components of the charging stock which are of unsatisfactory antiknock value, to a higher cracking temperature at substantial superatmospheric pressure in a separate heating coil, introducing at least a portion of the resultant highly heated products into a separate enlarged chamber operated at substantially reduced pressure relative to that employed in said reaction chamber, commingling said high-boiling fractions of the charging stock, without previously heating the same to cracking temperature, with the heated products supplied to said reaction chamber and maintaining the commingled materials in said reaction chamber at a sufficiently high cracking temperature and superatmospheric pressure to effect appreciable cracking of said high-boiling fractions in this zone, removing the resulting vaporous and liquid conversion products from the reaction chamber, subjecting the liquid products to appreciable further vaporization by supplying the same to said separate chamber, subjecting the vaporous conversion products, including those resulting from said further vaporization of the liquid products to fractionation independently of the charging stock for the formation of a single reflux condensate containing substantially all components of said vaporous products heavier than gasoline, subjecting fractionated vapors of the desired end-boiling point to condensation, recovering the resulting distillate and returning said reflux condensate formed by said fractionation, including intermediate liquid conversion products boiling above the range of said intermediate fractions of the charging stock, to the first mentioned heating coil for further cracking.
6. A process for the treatment of hydrocarbon oils which comprises subjecting raw oil charging stock for the process to fractional distillation and thereby separating the same into selected low-boiling, intermediate and high-boiling fractions,

- subjecting said intermediate fractions to cracking conditions of elevated temperature and superatmospheric pressure in a heating coil and communicating enlarged reaction chamber, removing the resulting vaporous and liquid conversion products from the reaction chamber, subjecting the liquid products to appreciable further vaporization in a zone of substantially reduced pressure relative to that employed in the reaction chamber, supplying said high-boiling fractions of the charging stock, without previously heating the same to cracking temperature, to said zone of substantially reduced pressure, recovering any components of said low-boiling fractions of the charging stock which boil within the range of gasoline and are of satisfactory antiknock value, heating the remainder of said low-boiling fractions, including any gasoline components of the charging stock which are of unsatisfactory antiknock value, to a higher cracking temperature at superatmospheric pressure in a separate heating coil, introducing at least a portion of the highly heated products into said zone of substantially reduced pressure, subjecting the total vaporous conversion products of the process, including the vapors evolved from said liquid conversion prod-

ucts and from said high-boiling fractions of the charging stock in said zone of substantially reduced pressure, to fractionation independently of the charging stock for the formation of a single reflux condensate containing substantially all components of said vaporous products heavier than gasoline, subjecting fractionated vapors of the desired end-boiling point to condensation, recovering the resulting distillate and returning said reflux condensate formed by said fractionation, including intermediate liquid conversion products boiling above the range of said intermediate fractions of the charging stock, to the first mentioned heating coil for further cracking.

7. A process such as defined in claim 6 wherein said liquid conversion products and said high-boiling fractions of the charging stock are reduced to coke in said zone of substantially reduced pressure.

8. A process such as defined in claim 6 wherein vaporous and liquid conversion products are withdrawn in commingled state from said reaction chamber and supplied to said zone of substantially reduced pressure.

CHARLES H. ANGELL.
